H. P. JESPERSON

OIL PUMP

Filed Dec. 26, 1925

Hans P. Jesperson
By Lynn H. Latte-Atty

UNITED STATES PATENT OFFICE.

HANS P. JESPERSON, OF SIOUX CITY, IOWA.

OIL PUMP.

Application filed December 26, 1925. Serial No. 77,719.

My invention relates to an automobile oil pump, and has for its object to provide a pump which is of simple, durable and inexpensive construction, and which is especially adapted to be attached to a particular type of automobile engine in common use.

More particularly, it is my object to provide in combination with an engine having a cylinder block provided with an integral time gear shell, including lateral wall portions inclined toward each other, and a flange forming, together with said wall portions and the cylinder block, a channel; a pump having one side engaged in said channel and against said walls, and its other side attached to the cylinder block in such a manner as to maintain the pump in engagement with said channel, the channel aiding to form a rigid support for the pump, and further to position the pump accurately relative to the crank shaft of the engine from which the pump is driven by suitable gearing mechanism.

Another object of the invention is to provide in combination with such an engine, a pump so mounted relative to the engine that either a gear drive or a drive from the fan belt may be used to supply power to the pump, and to rotate it in either case in the same direction.

Another object is to provide means for adjusting the pressure in the discharge pipe from the pump, whereby an oil gauge may be connected with said discharge pipe to indicate the flow of oil.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a perspective view of an engine to which the pump is attached.

Fig. 2 is a transverse sectional view through the forward end of the crank case of the engine, illustrating my invention attached, parts being broken away to better illustrate the construction.

Fig. 3 is a view similar to Fig. 2, illustrating an alternative drive for the pump.

Fig. 4 is a horizontal sectional view through the cylinder block, illustrating the

crank case and the pump and its connections in plan.

Fig. 5 is a detail sectional view, taken on the line 5—5 of Fig. 1.

Fig. 6 is a detail sectional view, taken on the line 6—6 of Fig. 3, and

Fig. 7 is a detail sectional view, taken on the line 7—7 of Fig. 4.

I have used the reference character 10 to indicate generally the crank case of a Ford automobile. The side flanges, 11, of the crank case co-act with flanges, 12, on the cylinder block, 13, in order that the two may be secured together by means of bolts, 14.

The cylinder front cover, 21, is secured by cap screws, 22, to the flange, 23, of the time gear shell, which includes a substantially vertical portion, 24, of the lateral wall which surrounds the large time gear and a downwardly and outwardly inclined portion, 25, curved to fit the small time gear.

A vertical boss, 26, having a forward transverse face is formed integrally with the cylinder block, 13, and forms, together with the wall portions, 24 and 25, and the flange, 23, a channel.

It will be understood that the parts herefore described are of the ordinary Ford engine construction.

My pump comprises a casing, A, having a lower semi-cylindrical side, 27, vertical sides, 28, and an upper side, 29, in which are threaded a nipple 30, and a T connection, 31, respectively, which form connecting means for the intake and discharge oil tubes, respectively, which will be hereinafter described.

The inner operating parts of the pump form no part of the present invention, and have therefore not been illustrated. These are enclosed by a plate, 32, which is secured to the casing, A, by means of screws, 33. (See Fig. 4.)

The pump is secured in place, relative to the engine, by inserting it in a plane transverse to the engine, with the side, 28, engaged against the wall, 24, and the periphery of the curved portion, 27, engaged against the wall, 25, the pump being of such thickness as to snugly fit between the forward face of the boss, 26, and the flange, 23. (See Fig. 4.)

The casing has a foot, 34, which is provided with a threaded opening, 35, shown in dotted lines in Fig. 2. A conical depres-

sion, 36, is formed in the casing, A, in position to receive the pointed end of a screw, 36^a, inserted in place of the ordinary screw, 22, through the right side opening provided 5 for it in the cover, 21. The depression, 36, is so located that pressure of the screw, 36^a, will draw the casing, A, laterally in snug engagement with the wall, 24. (See Figs. 4 and 7.)

10 The foot, 34, is of such length that after the screw, 36^a, has been tightened as above, a screw, 34^a, inserted in the opening for one of the bolts, 14, will draw it down into contact with the boss on the flange, 12, surrounding said opening and thereby draw the curved side, 27, of the casing, A, against the wall, 27.

15 The bolt, 34^a, prevents any lateral movement of the casing on one side, the boss, 26, and bolt, 36^a, on the other. The casing is thus held securely against vibration relative to the cylinder block, and yet may be applied or removed in a moment's time. Thus the pump forms a rigid part of the 20 engine when connected thereto.

25 The pump has an operating shaft, 37, which extends forwardly through a packing gland, 38, to a position substantially flush with the rear face of the fan drive 30 pulley, 39. The shaft is so positioned, as will be noted from an inspection of Figs. 2 and 3, that it may be either driven from a gear, 40, secured to the rear face of the pulley, 39, and meshing with the gear, 41, 35 which it carries, or by the ordinary fan belt, 42, engaging the left side of a pulley, 43, which it is adapted to also receive instead of the gear, 41.

40 The ratio between the diameters of the pulleys, 43 and 39, is the same as the ratio between the pitch diameters of the gears, 41 and 40, respectively. I find that with the pump positioned as described, and the pulley, 43, of such diameter as just mentioned, 45 the said pulley will intersect the normal path of the belt, 42, to such an extent as to gain sufficient traction therefrom for the proper driving of the pump.

45 The intake pipe, 44, is connected by a 50 pack nut, 45, to the nipple, 30, and by means of an elbow, 46, to the ordinary drain plug, 16, in the flywheel housing, 15. The plug is tapped and threaded to receive the elbow as shown in Fig. 5. An inverted cup-shaped screen 17, is received in the opening 55 in the plug above the elbow, 46, and strains the oil of impurities.

60 A discharge pipe, 47, is connected by means of a pack nut, 48, to one arm of the T connection, 31, and by means of a pack 65 nut, 49, to a nipple, 50, which is threaded into a boss on the cover, 21, which has an opening leading to the crank case interior. (See Fig. 3.)

65 Due to the fact that the oil discharge

opening is unobstructed and of rather large bore, it is necessary to provide a regulating device for building up the pressure in the discharge connection, 31, in order that the gauge, 51, which is connected to the T, 31, 70 by means of a tube, 52, may successfully indicate whether or not the pump is operating. For this purpose an opening is simply bored in the discharge arm of the connection, 31, and threaded to receive a 75 needle valve, 53, which serves to diminish or increase the cross-sectional area of the channel through the discharge arm of the connection, 31.

80 The gauge, 51, may be conveniently located on the dash of the car, and is merely indicated in Fig. 2 to show its use, the mounting forming no part of the invention.

85 My invention solves the problem of mounting an oil pump on the Ford engine with a minimum of trouble and expense, and is so arranged, relative to the engine, that the problem of driving it is very simply and effectively solved.

90 Some changes may be made in the construction and arrangement of the parts of my invention without departing from the real spirit and purpose of my invention, and it is my intention to cover by my claims 95 any modified forms of structure or use of mechanical equivalents which may be reasonably included in their scope.

I claim as my invention:

1. In combination with an automobile engine having a cylinder block, a crank case 100 having an opening to receive a forward crank case bolt for securing said block and crank case together, a cylinder front cover having an opening adapted to receive an intermediate right cap screw for securing 105 said cylinder cover to the cylinder block, the cylinder block having a time gear shell including substantially vertical and downwardly and outwardly inclined portions; an oil pump disposed in engagement with said 110 portions, means securing the pump in such engagement, said means including a screw engaging the pump through said cover opening, and a screw extending through said crank case opening and into the pump at 115 its free side for securing it to the block.

2. In combination with an automobile engine having a cylinder block provided with an integral time gear shell including a large 120 time gear shell wall having a substantially vertical portion and a small time gear wall joining said vertical portion at an angle extending downwardly and outwardly from said vertical portion, and said shell having 125 a flange forming, together with said walls and with the cylinder block, a channel; an oil pump having a side received in said channel and engaged against said walls, and means securing the pump against said walls.

3. In combination with an automobile en-

gine having a cylinder block provided with an integral time gear shell having a flange and having substantially vertical, and downwardly and outwardly inclined wall portions 5 forming, together with the cylinder block, a channel, said engine having a crank shaft extending forwardly of said shell; an oil pump having a side received in said channel and engaged against said walls, means for 10 maintaining the pump in engagement with said walls, and gearing connecting said pump with said fan drive pulley.

4. In combination with an automobile engine having a cylinder block, a crank case having an opening to receive a forward crank case bolt for securing said block and crank case together, a cylinder front cover 15

having an opening adapted to receive an intermediate right cap screw for securing said cylinder cover to the cylinder block, 20 the cylinder block having a time gear shell including substantially vertical and downwardly and outwardly inclined portions; an oil pump disposed in engagement with said portions, means securing the pump in such 25 engagement, said means including a screw engaging the pump through said cover opening, and means for securing the free side of the pump to the block.

Signed at Sioux City, in the county of 30 Woodbury and State of Iowa, this 19th day of December, 1925.

HANS P. JESPERSON.
